FREDERICK R. BROOKE ^{INVENTOR}
BY
STEPHEN J. COX ^{ATTORNEY}

UNITED STATES PATENT OFFICE.

FREDERICK R. BROOKE, OF BROOKLYN, NEW YORK.

DESIGN FOR A CARD.

SPECIFICATION forming part of Design No. 26,692, dated February 23, 1897.

Application filed January 9, 1897. Serial No. 618,656. Term of patent 3½ years.

To all whom it may concern:

Be it known that I, FREDERICK R. BROOKE, a citizen of the United States, residing at the city of Brooklyn, county of Kings, State of New York, have invented and produced a new and original Design for the Printing of Cards, of which the following is a specification.

In the accompanying drawing, reference to which is had herein, the figure is a plan view of my design applied to a card.

The leading features of my design consist of a series of polygonal panels B B' and curvilinear panels C C'. The upper and lower polygonal panels B' are extremely oblong in

form and the intermediate panel B nearly square, the medial curvilinear panels C being slightly elliptical and the upper and lower ones C' more elongated, having their greatest diameter at right angles to the greatest diameter of the medial panels C.

A represents the outline of the card upon which the design is printed.

What I claim is—

The design for a card herein shown and described.

FREDERICK R. BROOKE.
